Patented Mar. 29, 1921.

Edward M. Pauley,
INVENTOR.

D. J. Moore
ATTORNEY.

UNITED STATES PATENT OFFICE.

EDWARD M. PAULEY, OF BIRDSVIEW, WASHINGTON.

WRENCH.

1,373,201.

Specification of Letters Patent. Patented Mar. 29, 1921.

Application filed April 29, 1920. Serial No. 377,565.

To all whom it may concern:

Be it known that I, EDWARD M. PAULEY, a citizen of the United States, residing at Birdsvie, in the county of Skagit and State 5 of Washington, have invented certain new and useful Improvements in Wrenches, of which the following is a specification.

This invention relates to improvements in a pipe or nut wrench, and has for its object 10 the provision of means for readily adjusting the wrench to fit different sized pipes or nuts and firmly holding this adjusted position.

A further object of the present invention is to provide means for adjusting the jaw 15 members to fit a predetermined size of pipe or nut, and either to lock the same before or after the application of the tool to the work.

A still further object of the invention is to provide means for readily cleaning or 20 paring the working parts thereof.

Other objects and advantages will be apparent during the following description.

In this description like characters of reference refer to like parts in the accompanying 25 drawings in which:

Figure 1 is a longitudinal section of the device.

Fig. 2 is a plan of the preferred form.

Fig. 3 is a section on the line 3—3 of 30 Fig. 1.

Fig. 4 is a section on the line 4—4 of Fig. 1, with the tubular handle 14, rotated through an angle of 90 degrees.

Fig. 5 is a section on the line 5—5 of 35 Fig. 1.

Fig. 6 is a section on the line 6—6 of Fig. 1.

In the drawings wherein for the purpose 40 of illustration is shown a preferred embodiment of my invention the numeral 5 designates the usual adjustable head for use as a nut wrench, an alternate form 5' indicating a structure suitable for pipe work. The head member is mounted on a reduced shank 6, sliding within the recess 7, of the body 8. A further reduced portion 9 is toothed as at 45 10 to engage a toothed pair of segments 11, slidably inserted into the wedge-shaped slots 12 of the tubular handle 14. A still further reduced portion 15, slidably projects through the guiding collar 16, and terminates in stop member 17, as a cotter-pin or the like, to prevent withdrawal of the central shank 6. The member 15 has two 50 longitudinal slots 18 and 19, the function of which will be hereinafter more particularly

disclosed. Suitably secured within the handle is a spring member 20 bearing a lug 21 arranged to normally engage the slots 18 and 19 of the reduced portion 15 aforesaid. 60

At the fore part of the tubular handle the bore is interiorly enlarged forming an annular shoulder 22, against which the reduced end 24 of the body 8 seats when in use, while at the same time the exterior annular shoulder 25 of the body 8 abuts the extreme forward end of the handle as shown. 65

The reduced end of the body 24 carries radially disposed stops 26 operating through arcuate slots 27 in the fore part of the handle 70 and serving to limit the lateral rotation of the same to approximately a quarter turn.

To facilitate assembly and repair a door 28 is provided in the face of the handle, held in place by the screw 29. 75

Relative spacing of the head from the working face of the body is provided for by a suitable scale 30, etched or otherwise indicated on the shank 6.

To operate the wrench the handle is turned 80 in the direction of the arrow in Fig. 4 to the position indicated in this figure, wherein the teeth of the segments 11 are disengaged from the teeth of the reduced portion 9. The head 5 and the body 8 are then adjusted to the 85 work, or are spaced on the scale, and are locked in such spaced relation by a quarter turn of the handle in the opposite direction. Accidental interference of the toothed members during longitudinal adjustment of the 90 wrench is obviated by the engagement of the lug 21 in the slot 19 during such adjustment; while engagement of the lug 21 in the slot 18 positively holds the parts in the locked position. 95

It is to be understood that the form of device herewith shown and described is to be taken as a preferred embodiment of the same, and that various changes in the shape, size, and arrangement of the parts may be 100 resorted to without departing from the spirit of the invention or the scope of the appended claims.

Having thus described my invention what I claim is:

In a nut or pipe wrench of the character described, a tubular body having a work face at one end and a reduced portion at the other end, carrying projecting lugs; a tubular handle provided with a sleeve adapted to receive the reduced portion of the body, and having slots to receive said lugs, toothed 110

segments within the handle, guide means within the handle, a removable door in the side of said handle, and a resilient locking member carrying a lug and mounted within the tubular handle adjacent the door; a work head carried by a shank marked with a suitable measuring scale and reduced in size to slidably fit the tubular body portion, said shank being further reduced and provided 10 with locking teeth adapted to be engaged by

the toothed segments within the handle, and a still further reduced portion slidably mounted in the guide means aforesaid and terminating in a stop member adapted to abut the guide means, said reduced portion 15 having radially arranged, longitudinal slots adapted to be engaged by the aforesaid lug on the locking member.

In testimony whereof I affix my signature.
EDWARD M. PAULEY.
